DRAINAGE TRAY FOR SOAP OR THE LIKE

Julia Smith, 4812 Reynolds Drive,
Torrance, Calif. 90505

Filed Sept. 28, 1970, Ser. No. 25,229

Term of patent 7 years

Int. Cl. D6—06

U.S. Cl. D33—24

Fig. 1.

Fig. 2.

Fig. 3.

Fig. 4.

Fig. 5.

FIG. 1 is a front perspective view of a drainage tray for soap or the like showing my new design;

FIG. 2 is a top plan view;

FIG. 3 is a side elevation;

FIG. 4 is a cross section of FIG. 2 along lines 4—4; and

FIG. 5 is a rear elevation view.

I claim:

The ornamental design for a drainage tray for soap or the like, substantially as shown.
